CAR ROOF

Filed Jan. 22, 1932

UNITED STATES PATENT OFFICE

CHARLES DAVID BONSALE, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA

CAR ROOF

Application filed January 22, 1932. Serial No. 588,054.

This invention relates to car roofs of the all-steel riveted-up type wherein the roof sheets extend from side to side of the car and are rigidly connected along their adjacent 5 margins by upstanding seams, which function as outside carlines and have stiffening plates embodied therein for supporting beams that are alined with each other on opposite sides of said plates and carry load-10 lifting devices. The invention has for its principal objects to provide for the ready attachment of the beams to and their removal from the seam stiffening plates; to enable the stirrups that support the load-lifting devices to be slid along said beams from one to the other; and to provide for simplicity and cheapness of construction and compactness of design. The invention consists in the arrangements and combinations of parts 15 hereinafter described and claimed.

In the accompanying drawing, which forms part of the specification and wherein like symbols refer to like parts wherever they occur,

25 Fig. 1 is a vertical transverse section through a car roof embodying my invention,

Fig. 2 is a vertical longitudinal section through the roof at the ridge on the line 2—2 in Fig. 1,

30 Fig. 3 is an enlarged vertical transverse section through the ridge portion at the roof; and

Fig. 4 is an enlarged vertical longitudinal section through the ridge portion of the roof 35 in the region of one of the seams on the line 4—4 in Fig. 3.

Referring to the accompanying drawing, my invention is shown in connection with an 40 all-steel, riveted-up, single-course roof comprising metal roof sheets 1, that extend from side plate 2 to side plate 2 and slope downwardly from ridge to eaves where they are provided with depending flanges 3 that overhang and are riveted to such side plates. The 45 sides of the roof sheets are provided with raised panels 4 with upstanding seam flanges 5 along their outer edges.

Metal seam caps 6 of substantially inverted U-shaped cross-section straddle the adjacent side marginal seam flanges 5 of the roof

sheets 1 and are rigidly secured to said flanges by horizontal rivets 7, whereby the seam caps and seam flanges cooperate to form rigid upstanding seams that function as outside carlines for the roof. The seam caps are provided with outstanding base flanges 8 that rest on the raised side marginal panels 4 of adjacent roof sheets and are turned down at the eaves over the depending eaves flanges 3 of said sheets. As 55 shown in the drawing, the seam flanges 5 are of uniform depth for the greater portion of their length; and the seam caps 6 are preferably of greater depth at the ridge than at the eaves and their base flanges 8 are wider 60 at the eaves than at the ridge.

A running board extends longitudinally of the car at the ridge and preferably comprises sections 9 located between adjacent 70 seams with their ends supported on the horizontal top flanges of angle brackets 10 whose vertical flanges are rigidly secured to the sides of the seam caps 5 by the securing rivets 7 therefor.

Additional strength and rigidity are imparted to the roof by embodying in the upstanding seams thereof seam stiffening members in the form of metal plates or strips 11. The seam stiffening plates 11 are located between the adjacent upstanding roof sheet 75 flanges 5 and are rigidly secured within the seams by the rivets 7 that secure the seam caps 6 to said roof sheet flanges. At the ridge portion of the roof, the seam stiffening plates extend below the roof sheets.

Extending longitudinally of the car immediately beneath the roof at the ridge are load-lifting beams 12 that are alined with each other on opposite sides of the seam stiffening plates 11. The load-lifting beams 12 are preferably of inverted channel-shaped cross-section and are provided at the lower edges of their side walls with outstanding base flanges 13. Each beam 12 extends between the stiffening plates 11 of adjacent roof seams with its ends supported on brackets 14 that are removably secured to said plates by bolts 15. As shown in the drawing, the beam supporting brackets 14 are of 90 angle shape and are arranged with one 95

flange bearing flatwise against the side of the hanger plate and with the other flange disposed uppermost and extending outwardly to form a support for the end of the beam whose 5 web portion rests thereon.

The base flanges of the beams are adapted to be slidably engaged by a stirrup 16 adapted to support a lifting tackle or other load-lifting device (not shown). The hanger or 10 seam stiffening plates 11 are notched on opposite sides of the beams so as to provide spaces 17, which permit the stirrup 16 to be slid from the end of the beam located on one side of a plate onto the end of the beam located on the other side of said plate, thereby 15 permitting a single stirrup to be slid along the flanges of every one of the alined beams.

By the arrangement described, the beams 12 serve to support the roof sheets between 20 seams; and they also serve to slidably support the stirrup 16 to which the lifting tackle or other device is secured. The stirrup may be slid along all of the beams by reason of the openings 17 formed in the plates 11 on opposite 25 sides of said beams, thereby dispensing with the use of a separate stirrup for each beam. The beams merely rest upon the brackets 14 which are removably secured to the hanger plates, thereby permitting the beams 30 to be quickly and easily attached to and removed from the roof.

What I claim is:

1. A car roof comprising roof sheets connected along their adjacent margins by seams, 35 plates embodied in said seams, beams extending from seam to seam beneath said roof sheets, said beams being alined with each other on opposite sides of said plates, means for supporting the adjacent ends of said beams from the plates located therebetween, 40 said means comprising brackets that are removably secured to the opposite sides of said plates with their outturned flanges uppermost and freely support the adjacent ends of said beams.

2. A car roof comprising roof sheets extending from eaves to eaves of the car and connected along their adjacent margins by upstanding seams, plates embodied in said 50 seams, beams extending longitudinally of the car in contact with the undersides of said roof sheets; said beams being alined with each other on opposite sides of said plates, and means for removably supporting the adjacent ends of said beams from the plates disposed therebetween, said means comprising brackets that are removably secured to the opposite sides of said plates and freely support the adjacent ends of said beams.

3. A car roof comprising roof sheets connected along their adjacent margins by upstanding seams, plates embodied in said seams and having portions extending below the roof sheets, inverted channel-shaped beams extending longitudinally of the car beneath 65

said roof sheets, said beams being alined with each other on opposite sides of said plates, and means for removably supporting the adjacent ends of said beams from the portions of the plates located therebetween, said means comprising brackets that are removably secured to the opposite sides of said plates and have outstanding flanges that extend into the adjacent ends of said beams beneath the webs of the inverted channels therein. 70

4. A car roof comprising roof sheets connected along their adjacent margins by upstanding seams, plates embodied in said seams, beams extending between the plates of adjacent seams, said beams being alined with each other on opposite sides of said plates, means for removably supporting the adjacent ends of said beams on opposite sides of said plates, and means slidable along said beams for supporting a load-lifting device, said plates being arranged to permit said means to be slid from one beam to another. 80

5. A car roof comprising roof sheets connected along their adjacent margins by upstanding seams, plates embodied in said seams and extending below the roof sheets, beams extending between adjacent plates beneath said roof sheets and alined with each other on opposite sides of said plates, a member slidable along said beams for supporting a load-lifting device, and means whereby said member is adapted to be slid from one beam to another. 90

6. A car roof comprising roof sheets connected along their adjacent margins by upstanding seams, plates embodied in said seams extending below said sheets, beams extending longitudinally of the car beneath said roof sheets, said beams being of inverted channel-shaped section with lateral flanges, said beams being alined with each other on opposite sides of said plates, and a member slidable along said beams for supporting a load-lifting device, said plates being notched adjacent said flanges to permit said member to be slid from one beam to the other. 100

7. A car roof comprising roof sheets extending from eaves to eaves of the car and connected along their adjacent margins by rigid upstanding seams, plates embodied in said seams and extending below the roof, load-lifting beams extending longitudinally of the car beneath the roof, said beams being alined with each other on opposite sides of the plates embodied in said seams, and a member slidable along said beams, said seam plates being arranged to permit said member to be slid from one beam to the other. 115

8. A car roof comprising roof sheets connected along their adjacent margins by seams, plates embodied in said seams and extending below the roof, load-lifting beams extending from seam to seam beneath and in contact with the roof, said beams being of inverted channel-shaped section and being alined with 125

each other on opposite sides of said plates, and brackets removably secured to the opposite sides of said plates and having outstanding flanges extending within and supporting 5 the ends of adjacent beams.

9. A car roof comprising roof sheets connected along their adjacent margins by seams, plates embodied in said seams and extending below the roof, load-lifting beams extending 10 from seam to seam beneath the roof, said beams being of inverted channel-shaped section and being alined with each other on opposite sides of said plates, brackets removably secured to the opposite sides of said 15 plates and having outstanding flanges adapted to support the ends of adjacent beams, said beams being provided with outstanding flanges at the lower edges of their side walls, said plates having notches in their lower 20 edges to provide clearance above and beyond said flanges; and a stirrup slidable along said beams through said notches.

10. A car roof comprising roof sheets connected along their adjacent margins by seams, 25 plates embodied in said seams and extending below the roof, and load-lifting beams extending from seam to seam beneath the roof in alinement with each other on opposite sides of said plates, said beams being of inverted channel-shaped section with outstanding flanges at the lower edges of their side walls, and a stirrup slidable along said beams, 30 said plates being cut away above and at the outer edge of the side flanges of said beams 35 to permit said stirrup to be slid from one beam to another.

Signed at New Kensington, Pennsylvania,
this 18th day of January, 1932.

CHARLES DAVID BONSALL.
